EXTENSIBLE BRACELET CLASP

John Dalo, Providence, R. I., assignor to A and Z
Chain Company, Providence, R. I., a corpora-
tion of Rhode Island

Application March 4, 1937, Serial No. 129,023

9 Claims. (Cl. 24—71)

The present invention relates to an extensible clasp for connecting the ends of watch-bracelets or the like and consists in improvements in clasps of the type illustrated and described in my prior 5 application for United States Letters Patent, Serial No. 33,594, filed August 30, 1935.

One of the objects of the present invention is to provide an extensible clasp of the type indicated having a slide freely movable in the clasp 10 in one direction to contract its length and yieldingly held in adjusted relationship to snugly fit the bracelet to the wrist of the wearer.

Another object of the invention is to provide an extensible clasp of the type indicated in which 15 the adjusting means are wholly enclosed when the clasp is applied to the wrist to prevent accidental release of the adjustment.

Another object of the invention is to provide a clasp of the type indicated having a resilient 20 pawl member mounted for movement on the slide and yieldingly held against abutments on the slide to provide a resilient connection therebetween.

Another object of the invention is to provide a clasp of the type indicated having a toothed 25 rack on one clasp member which overlies and is engaged by the resilient pawl on the slide, being so constructed and arranged as to permit the pawl to be depressed and slid by the teeth on the rack to release the slide.

Still another object of the invention is to provide a simple and compact construction and arrangement of the elements which facilitates the manufacture and assembly of the parts.

These and other objects will become more apparent from the following description of two embodiments of the invention illustrated in the accompanying drawings. It is to be understood, however, that the drawings are for purposes of 40 illustration only and not a definition of the limits of the invention, reference being had for this purpose to the appended claims. In the drawings:

Fig. 1 is a plan view of a two-part bracelet 45 connected by the extensible clasp forming the subject-matter of the present application;

Fig. 2 is a longitudinal sectional view of the clasp showing its pivoted sections in extended 50 relationship and illustrating in dash lines the manner in which the sections are folded into overlying relationship;

Fig. 3 is a bottom plan view of the clasp showing a portion thereof as broken away to indicate the relationship of the parts and the ar- 55

angement of the compression springs which yieldingly connect the pawl to the slide;

Fig. 4 is a part sectional view of the clasp showing the slide withdrawn with respect to the pawl and the connecting springs compressed; 5

Fig. 5 is a sectional view similar to Fig. 2 illustrating the manner in which the pawl is depressed to release the rack-teeth and cause the slide to be withdrawn from its housing;

Fig. 6 is an enlarged transverse sectional view 10 taken on line 6—6 of Fig. 1 showing the pawl on the latching plate engaged with one of the teeth on the rack;

Fig. 7 is an enlarged transverse sectional view 15 taken on line 7—7 of Fig. 1 showing the slotted construction of the latching plate which gives it the necessary resiliency;

Fig. 8 is a perspective view of the housing member of the clasp and the slide in disassembled 20 extended relationship;

Fig. 9 is a top plan view of a modified construction of clasp in which the pivoted sections are folded and nested in the housing through an opening in the top thereof; and

Fig. 10 is a side view of the modified form of 25 clasp illustrated in Fig. 9 with the housing shown partly in section to indicate the relationship of the parts.

Referring to Fig. 1 of the drawings, the clasp member 10 forming the subject-matter of the 30 present application is shown as connecting the ends of the sections 11 and 12 of a two-part bracelet. The bracelet sections as herein illustrated comprise a plurality of flexibly-connected links having terminal connectors 13 at their outer 35 ends for attachment to the bails of a wrist-watch, not shown, but it is to be understood that any other prevailing style of bracelet may be used with the clasp, such as a fabric, leather, mesh or like strap, and the terminal connectors 13 may 40 take other forms.

The preferred embodiment of the extensible clasp 10, illustrated in Figs. 1 to 8, is comprised of a plurality of foldable sections including a body member or housing 14, a pair of cooperating slide- 45 members 15 and 16 forming a connecting link, and an end section 17. The body member or housing 14 is formed with a top plate 18, preferably of sheet-metal, curved longitudinally throughout its length to conform to the contour 50 of the wrist. The plate 18 has opposite side portions 19 and 20 folded downwardly and then inwardly in flanges 21 and 22 having their edges terminating in parallel spaced-apart relationship, see Figs. 6 and 7. The top plate 18, to- 55

gether with the folded sides 19 and 20, provide longitudinally-extending channels 24 and 25 at the opposite sides of the body member. At one end the plate portion 18 has a narrow lip 26 extending beyond the folded sides 19 and 20 and adapted to be bent over for a purpose as later explained, see Fig. 8, while the opposite end of the plate portion 18 has a curved lip 27, see Figs. 1 and 4, to provide a finger-piece for 10 prying the clasp open. A pivot-pin 28 extends between the folded sides 19 and 20 of the plate 18 at the end of the body member 14 adjacent the finger-piece 27.

The member 15 forming one part of the connecting link is of rectangular shape with a centrally-depressed groove 32 extending throughout the greater portion of its length and forming side rails 33 and 34. The member 15 is pivotally connected to the body member 14 by spaced loops 35 at its end embracing the pivot-pin 28, and the side rails 33 and 34 are adapted to slide in lateral channels 36 and 37 of usual construction at the sides of the link member 16. The relative sliding movement of the members 15 and 16 is limited by the engagement of a 25 detent 38 on the member 16 with the opposite ends of the groove 32 in the member 15 into which the detent projects. The channeled sides of the member 16 extend beyond its plate portion and the extended ends are flattened and pierced to form apertured ears 40 for pivotal connection with the end section 17 of the clasp.

The end section 17 comprises a base plate 41 with its opposite sides 42 and 43 folded upwardly to provide projecting flanges. At one end, the plate 41 is slotted adjacent the sides 42 and 43 to receive the ears 40 on the member 16 and the material of the plate between the slots is curled around to form a loop 39. A pin 44, riveted in 40 holes in the side flanges 42 and 43, extends through the loop 39 at one end of the end section 17 and the apertured ears 40 on the link member 16 for pivotally connecting the link member and end section. The end section 17 is substantially equal in width to that of the space 45 between the parallel edges of the flanges 21 and 22 on the body member or housing 14 and the flanges 42 and 43 on the section 17 have detents 45 for cooperation with these edges. The opposite end of the end section 17 has a loop 46 for 50 embracing the end link of the bracelet section 12 to provide a flexible connection therewith.

As thus far described the clasp is not materially different from those heretofore used, the link members 15 and 16 being adapted to telescope one into the other and together with the end section 17 to fold into the body member or housing 14 in overlying relationship in the manner indicated by dash lines in Fig. 2; the link members and end section being curved throughout their length to conform to the longitudinal curvature of the body member. As shown in Figs. 6 and 7, the link members 15 and 16 lie wholly between the flanges 42 and 43 on the end section 17 and the flanges 42 and 43 lie wholly between the terminal edges of the folded flanges 21 and 22 at the sides of the body member 14. The several sections of the clasp are latched together in folded relationship by the engagement of the detents 45 on the side flanges 42 and 43 of the end section 17 with the edges of the flanges 21 and 22 on the folded sides 19 and 20 of the body member 14.

The present invention is directed particularly 75 to the adjustable feature of the clasp to adapt

it to be manually contracted in length and to provide a resilient yielding action to permit a limited expansion and contraction in its length when the parts are in adjusted relationship. To this end a slide 50 in the form of a U-shaped or bifurcated frame shown in inverted position in Fig. 8 is mounted in the body member 14 for relative longitudinal movement with respect thereto. The slide 50 is preferably stamped from flat stock to form spaced side rails 51 and 52 10 with a crossbar 53 at one end, the side rails 51 and 52 being of proper dimensions throughout the greater portion of their length to adapt them to fit in the channels 24 and 25 of the body member or housing 14. At their free ends the 15 side rails 51 and 52 have reduced shank portions 54, preferably shaped during the stamping operation and forming spaced shoulders 55 and 56. The crossbar 53 is also reduced in cross-sectional area at its central portion to adapt it to receive 20 a loop 57 at the end of the bracelet section 11 curled therearound to provide an articulated connection.

A latching member 60 is mounted on the slide 50 for relative movement thereon, the latching member being assembled on the slide before the latter is inserted into the body member or housing 14. The latching member 60 is comprised of a resilient plate of appropriate width to adapt it to fit the opening between the side rails 51 and 52 and having lateral wing portions folded or bent around to form bearings 62 and 63 which loosely embrace the reduced shanks 54 of the side rails. At one end of the plate 60 a portion of the material is struck up from the plane of the plate to form an inclined detent or pawl 64. The plate 60 is slotted in U-shape at the rear of the pawl 64 to form a tongue 65 which is depressed from the plane of the plate at the side opposite from the pawl. The tongue 65 bears against the top of the housing 14 to yieldingly press the main portion of the plate 60 with the pawl 64 downwardly at an angle thereto, the loose connection of the bearings 62 and 63 with the shanks 54 permitting a limited rocking movement of the plate. The forward edges of the 40 bearings 62 and 63 are yieldingly held in abutting engagement with the shoulders 55 on the spaced rails 51 and 52 of the slide 50 by coiled compression springs 66 acting between the opposite edges of the bearings 62 and 63 and the shoulders 50 56 adjacent the ends of the rails. The springs 66 are coiled around the rails 51 and 52 and form a yielding connection between the slide 50 and latching member 60 to normally hold the members in predetermined relationship but yielding to allow a limited relative movement therebetween.

As another feature of the invention a toothed rack-plate 70 is provided to serve the double function of retaining the slide 50 in assembled relationship in the body member or housing 14 and cooperating with the pawl 64 to hold the slide in adjusted position. As illustrated most clearly in Fig. 8, the rack-plate 70 is of a width substantially equal to or slightly less than the distance between the marginal edges of the inturned flanges 21 and 22 on the housing 14. The plate 70 is hingedly mounted at one end on the pivot-pin 28 at the end of the housing 14 by means of a curled ear 71 which embraces the pin between the spaced loops 35 of the pivoted section 15, see Figs. 4, 5 and 8. The plate 70 is slotted longitudinally at 73 and formed with a series of transverse slots to provide two rows of teeth 72 with 75

5 a clearance space extending centrally there-between. In other words, the teeth 72 are formed by opposite rows of projections which extend inwardly toward each other with spaces between their ends forming a continuous slot throughout the length of the toothed portion of the rack-plate. The opposite free end of the plate 70 is curved upwardly at 74 and has a lug 75 bent downwardly across its edge. The rack-plate 70 10 is normally held in the position illustrated in Figs. 2 and 5 by the narrow lip 26 at the end of the housing or body member 14, which is bent back over its curved end 74; an aperture 76 being provided in the lip 26 through which the lug 75 on the plate extends. With the free end of the 15 rack-plate 70 rigidly held by the curled lip 26 the rack-teeth 72 overlie and are yieldingly engaged by the inclined pawl 64 on the latching member 60. A preferred form of construction 20 having now been described in detail, the method of assembling the parts and the mode of operation of the complete clasp will be next explained.

25 The latching plate 60 is first mounted on the slide 50 by folding its lateral wings about the reduced shanks 54 of the side rails 51 and 52 to provide the bearings 62 and 63. The springs 66 are then applied to the reduced shanks 54 and compressed between the shoulders 56 and the bearings 62 and 63 to assemble the parts in a self-contained unit. It will be understood that the 30 springs 66 may be slid over the ends of the shanks 54 and the ends thereof thereafter staked, spread or upset to form the shoulders 56 to retain the springs in position. The assembled unit comprising the slide 50 and latching member 60 is then slid into the body member or housing 14. The pivoted rack-plate 70 is next connected to the pivot-pin 28 and folded downwardly to cause it to lie in the housing 14 between the edges of the flanges 21 and 22 and its curved free end 74 35 to enter the opening between the spaced side rails 51 and 52 of the slide 50. The rack-teeth 72 will then overlie and be positioned to be engaged by the yielding pawl 64. The free end 74 of the rack-plate 70 is attached to the body or housing member 14 by bending back the lip 26 to cause the lug 75 to enter the slot 76. The rack-plate 70 is thus fixedly connected at both ends to the body member 14 and the engagement of the pawl 64 with one of the rack-teeth 72 acts to yieldingly 40 hold the slide 50 against withdrawal from the housing 14 due to the springs 66 which connect the latching member 60 with the slide. The several folding members 15, 16 and 17 are then connected to the housing 14 in the manner as previously explained.

45 To apply the clasp to the wrist when connected to the opposite ends of the bracelet sections 11 and 12 the articulated sections 14, 15, 16 and 17 are unfolded and the bracelet slid over the hand of the wearer. The clasp is then closed by first sliding the member 15 telescopically on the member 16 and folding the sections 14, 15, 16 and 17 together in the manner indicated by the dash lines in Fig. 2. The end section 17 is pressed into the body member or housing 14 to cause the detents 45 to snap by the opposed edges of the flanges 21 and 22 to latch the parts in folded relationship. In this folded relationship of the parts the member 16 rests against the rack-plate 70, see Figs. 6 and 7, and the adjusting means is wholly enclosed within the clasp body or housing 14.

50 The slide 50 may then be telescoped within the body member 14 to contract the clasp to adjust

5 the length of the bracelet to conform to the size of the wrist. The two parts of the clasp are moved into contracted relationship by manually pressing the fingers against the end of the slide 50 and the opposite end of the member 14. During this inward movement of the slide 50 with respect to the body member 14 the inclined detent or pawl 64 slides across the teeth 72 on the rack-plate 70. Due to the pressure of the resilient tongue 65 on the latching member 60 against the top of the housing 14 the pawl 64 is yieldingly held in contact with the teeth 72 on the rack as it slides thereover. The contraction of the clasp is continued until the bracelet fits the wrist snugly, at which time the end of the inclined pawl 15 64 engages one of the teeth on the rack-plate 70 to latch the slide in adjusted relationship with respect to the body member 14.

20 With the clasp closed as above described, the slide 50 may have a limited movement of extension and retraction to compensate for the flexing of the wrist as the springs 66 expand and contract between the abutment shoulders 56 on the side rails of the slide and the bearings 62 and 63 on the latching plate 60. As the slide 50 is extended 25 from the body member 14 it moves with respect to the latching member 60 and rack-plate 70 against the compression of the springs 66 and has a range of movement as indicated in Figs. 3 and 4. Retraction of the slide into the body member 30 14 by the springs 66 is limited by the engagement of the shoulders 55 on its side rails 51 and 52 against the bearings 62 and 63. In this manner the slide 50 is yieldably extendible with respect to the rack-plate 70 and body member 14 to which 35 it is latched to adapt the length of the bracelet to be automatically adjusted within definite limits. When once adjusted the slide cannot be accidentally released as the latching member 60 and rack-bar 70 are wholly enclosed within the clasp housing 40 14.

45 When the bracelet is to be removed from the wrist the finger-nail is inserted under the lip 27 on the body member 14 to pry the latter away from the end section 17. The sections of the 50 clasp may then be extended as shown in Figs. 2 and 3 and the bracelet removed over the hand. When again applied to the wrist and collapsed the clasp will be properly adjusted to fit the wrist due to the latching engagement of the pawl 64 55 with a pair of the teeth 72 on the rack-plate 70. In other words, when once adjusted the clasp will retain its adjustment even though its sections are folded and unfolded many times. If however, the bracelet is found to be too tight or if 60 for any other reason it is desired to extend the length of the clasp the detent or pawl 64 may be depressed to release it from the teeth 72 on the rack-plate 70. To accomplish this result any sharp pointed instrument such as a pen knife 60 may be inserted in the slot 73 extending longitudinally of the teeth 72 and pressed angularly against the pawl 64 to depress it against the resilient action of the tongue or angularly related leaf 65 which normally holds the pawl in engagement with the teeth. By pressing the instrument against the pawl 64 in this manner the slide 50 65 may be slid in the housing or body member 14 to extend it therefrom during which movement the point of the implement 60 slides in the longitudinal slot 73. The extension movement of the slide 50 is limited by the engagement of the end of the latching member 60 with the curved end 74 of the rack-plate 70, which is attached to the lip 26 on the housing member 14. After the slide 50 has 70 75

been extended from the housing 14 and the detent or pawl 64 released the length of the bracelet can be readjusted in the manner as previously explained by telescoping the slide into the body member 14 to the extent required, this adjustment being accomplished with the bracelet on the wrist with the inclined pawl 64 sliding freely over the teeth 72 on the rack-plate 78.

In the modified form of clasp illustrated in Figs. 9 and 10 the body member 14 is of inverted construction as compared to that first described. The sides of the bottom plate of the body portion 14 are folded upwardly and inwardly instead of downwardly and inwardly to form an opening 80 on the top of the clasp into which the articulated sections 16 and 17 are folded. The section 17 is provided with detents 45 for holding the parts latched within the housing 14 and includes a lip 82 to be engaged by the finger-nail to pry the end section 17 away from the body member or housing. In other words, in the embodiment of the invention illustrated in Figs. 9 and 10 the articulated sections are folded one over the other and nested in the top of the body member or housing 14 instead of in the bottom of the housing 14. The method of assembling the parts and the mode of operation of this construction, however, is substantially identical with that described with respect to the first form of the invention.

Although the sections of the clasp have been described as preferably made of sheet-metal stamped out and folded to shape, it is to be understood that they may be made of any other suitable material whether molded, pressed, or otherwise formed. It is also to be understood that the clasp may be made without the foldable sections, that is, as including only the housing or body member 14 and the slide 58, and still be within the scope of the present invention.

The invention having now been described in two of its forms, it will be observed that an improved clasp is provided having a simple and compact structure which lends itself to economical manufacture and assembly. It will also be observed that a novel form of resilient pawl and rack is provided which permits the slide to be freely slid in one direction to adjust the length of the clasp while yieldingly holding the slide against movement in the opposite direction; an outstanding advantage of this construction being that the clasp may be adjusted on the wrist and when once adjusted will retain its adjustment for repeated applications of the bracelet to and its removal from the wrist. Moreover, the yielding action of the clasp provides a more comfortable fit of the bracelet on the wrist without binding or pinching when the wrist is flexed.

Although only two embodiments of the invention are herein shown and described, it is to be noted that other variations may be made in the form and arrangement of the parts of the device within the spirit and scope of the invention. Therefore, without limiting myself in this respect, I claim:

1. In an extensible clasp for bracelets, a clasp member, a slide in the clasp member having side rails with an opening therebetween, said side rails having spaced shoulders, a resilient pawl in the opening in the slide having bearings embracing the side rails and slidably between the shoulders, a toothed rack fixed to the clasp member and overlying the pawl, and a compression spring on each side rail acting between one of the shoulders and a bearing on the pawl to yieldingly hold

the bearings in abutting engagement with the opposite shoulders.

2. In an extensible clasp for bracelets, a clasp member, a slide in the clasp member having side rails with an opening therebetween, a latching member in the opening in the slide having angularly-disposed resilient portions and bearings at its sides embracing the side rails, a rack-plate fixed to the clasp member and overlying the latching member, one of the resilient portions of the latching member bearing against the clasp member and the other portion having a detent yieldingly held in engagement with the rack-plate whereby the slide may be slid into the clasp member and held against outward movement by the detent, and compression springs on the side rails engaging the bearings on the latching member to yieldingly hold the slide in adjusted position.

3. In a device of the type indicated, a clasp member, a slide on the clasp member having side rails with an opening therebetween, a resilient pawl in the opening having bearings embracing the side rails of the slide, resilient means for yieldingly holding the pawl in predetermined position on the slide, and a plate attached to the clasp member and overlying the pawl, said plate having rack-teeth engaged by the pawl and a slot extending transversely of the rack-teeth through which a tool may be inserted to depress the pawl out of engagement with the rack-teeth and thereby release the slide for movement in the clasp member.

4. In a device of the type indicated, a clasp member having channels at its sides, a slide having side rails slidable in the channels, a resilient pawl positioned between the side rails and having bearings at its opposite sides embracing the side rails, a plate in the clasp member having rack-teeth, and interengaging means on the clasp member and plate for holding the latter with the rack-teeth in operative position with respect to the pawl and the slide in assembled relation in the clasp member.

5. In a device of the type indicated, a clasp member, a plate on the clasp member having rack-teeth, pivot-means for attaching one end of the plate to the clasp member, detachable holding means on the clasp member for engaging the free end of the plate whereby said end may be released and the plate swung on its pivot, a slide mounted between the clasp member and plate, and a resilient pawl on the slide cooperating with the rack-teeth on the plate to hold the slide in adjusted position on the clasp member.

6. In an extensible clasp for bracelets, a clasp member, a slide having spaced side rails with an opening therebetween and mounted to slide on the clasp member, a resilient pawl in the opening between the side rails of the slide, means at the sides of the pawl for connecting it to the side rails of the slide, and a toothed rack-plate disposed in the opening between the side rails of the slide overlying the resilient pawl to enclose the latter between it and the clasp member, said rack-plate having its opposite ends attached to the clasp member to retain the pawl and slide assembly in the clasp member.

7. In an extensible clasp for bracelets, a clasp member, a slide having spaced side rails with an opening therebetween and mounted to slide on the clasp member, a resilient pawl disposed in the opening between the side rails and having bearings at its sides embracing the side rails to

slide thereon, a toothed rack attached to the clasp member and overlying the resilient pawl, and resilient means for yieldingly holding the pawl in predetermined position on the slide.

5. 8. In an extensible clasp for bracelets, a clasp member, a slide mounted to slide on the clasp member and having spaced side rails with an opening therebetween, a latching member in the opening between the side rails of the slide and having bearings at its sides embracing the side rails for sliding movement thereon, said latching member having angularly-disposed resilient portions with one of said portions bearing against the clasp member and the other portion constituting a detent, a toothed rack attached to the clasp member and overlying the detent on the latching member for cooperation therewith, and resilient

means for yieldingly holding the latching member in predetermined position on the slide.

9. In a device of the type indicated, a clasp member, a slide in the clasp member having side rails with an opening therebetween, a resilient pawl positioned in the opening between the side rails and connected to the latter, and a plate overlying the pawl in the opening between the side rails of the slide and having its opposite ends attached to the clasp member, said plate having 10 rack-teeth adapted to be engaged by the pawl and a slot extending transversely of the rack-teeth through which a tool may be inserted to depress the pawl out of engagement with the rack-teeth and thereby release the slide for movement in the clasp member. 15

JOHN DALO.
